GIRDLE

Lois Florence Campbell, New York, N. Y., assignor to Treo Company, Inc., New York, N. Y., a corporation of New York

Application December 21, 1937, Serial No. 180,933

2 Claims. (Cl. 2—37)

My invention relates to a new and improved girdle, which may or may not have a brassière portion.

One of the objects of my invention is to provide 5 a new and improved girdle which is integral with a brassière.

Another object of the invention is to provide a 10 girdle having the required elasticity at the bottom portion, and also at the bust portion, if the garment is of the combination type.

Another object of the invention is to provide a garment which can be simply manufactured at low cost.

Other objects of my invention will be set forth 15 in the following description and drawing which illustrate a preferred embodiment thereof, it being understood that the above statement of the objects of my invention is intended generally to explain the same without limiting it in any 20 manner.

Fig. 1 is a front elevation of the improved garment.

Fig. 2 is a rear elevation.

Fig. 3 is a sectional view on the line 3—3 of 25 Fig. 1.

The garment is provided with a front panel 1, a rear panel 2, and side panels 3.

The side panels 3 are made of elastic woven material or the like, so that said panels 3 are 30 stretchable both vertically and horizontally. Material of this type which is woven from elastic yarns is well known in the trade as two-way stretch material.

The major portion of the front panel 1 is made 35 of closely woven material 4 which is stretchable and elastic vertically and which is substantially non-stretchable horizontally. Woven material of this type is well known in the trade under the name of one-way stretch material.

The bottom portion of the front panel is shaped 40 so as to provide tapered projections or darts 5. These projections may be triangular or they may have any other shape so as to provide space for the intermediate darts 6 of a supplemental strip

45 of two-way stretch elastic material. Said supplemental piece of material is sewed to the inner surface of the front panel, above the tops of the darts 5. This supplemental piece of material is sewed to the front panel, at and below the tops of 50 darts 5, only along the edges of the darts 5. Said piece of material 6 underlies the front panel 1.

The bottom portion of the front of the garment, at and below the tops of darts 5, is therefore stretchable both horizontally and vertically.

55 The supplemental material is horizontally

stretchable and elastic, although darts 5 are non-stretchable in the horizontal direction. The darts 5 and 6 are both vertically stretchable. Since the supplemental material is unconnected to or free from darts 5, save along the edges of said darts 5, sufficient horizontal stretch and elasticity are provided. These improvements apply to a girdle or garment of any type, and they are not limited to a girdle or garment which has a bust portion.

The top or brassière part of the combination garment which is illustrated in the drawing, is made of non-stretchable mesh material 10 which is sewed to the elastic side panels and which is sewed to the material of the front of the garment along the edges of the projections 11. These projections 11 are vertically elastic and substantially non-stretchable in the horizontal direction. The mesh material 10 is not located at the inner faces of projections 11, save where it slightly overlaps the edges of said projections, in order to connect said edges by stitches to said mesh material 10.

The rear panel 2 is made of woven material 7 which is vertically elastic and stretchable and which is substantially non-stretchable in the horizontal direction. Said material 7 is shaped so as to form darts 1a. Said material 7 may be elastic and stretchable only in the horizontal direction, and non-elastic and non-stretchable in the vertical direction.

The top portion of the rear of the garment is provided with a strip of two-way stretch material which is elastic both vertically and horizontally, thus forming darts 8 which are stretchable both vertically and horizontally. This supplemental strip of material is sewed to the material 7, only along the edges of the darts 1a, and it is also sewed to the side panels 3.

Hence the top of the garment, at and above the bottom ends of darts 1a is stretchable both horizontally and vertically, even though darts 1a have only one-way stretch, either horizontally or vertically.

The darts 5 reinforce the two-way stretch construction at the bottom of the garment, and said 45 darts 5 limit the horizontal stretch and elasticity at the bottom of the garment, since said darts are stretchable only in the vertical direction.

The supplemental material lies substantially flat against darts 5 and 1a.

This combination of one-way stretch darts or members (having any shape) and provided with intermediate darts or members, can be used in any part of a girdle or garment, although it is 55

preferred to use said combination only at the top and at the bottom of the garment.

The darts 5 and 7a form, in effect, spaced members of one-way stretch material, having intermediate members of two-way stretch material.

When I specify that the panel 1 is vertically elastic, I do not wish to be limited to the use of one-way stretch material, unless the use of such one-way stretch material is specified in a claim or 10 claims. The projections 11 are longitudinal and lateral.

I claim:

1. A combination girdle and brassière having a front panel made of material which is elastic in 15 the vertical direction, the brassière portion of said

garment being made of substantially non-stretchable material, said panel having projecting portions thereof located in and interrupting said material of the brassière portion and connected to said material of the brassière portion. 5

2. A combination girdle and brassière having a front panel made of material which is elastic in the vertical direction, the brassière portion of said garment being made of substantially non-stretchable material, said panel having projecting portions thereof located in and interrupting said material of the brassière portion and connected to said material of the brassière portion, said projecting portions having lateral extensions. 10

LOIS FLORENCE CAMPBELL. 15
